UNITED STATES PATENT OFFICE.

HALDIMAND W. NEAL, OF MANSFIELD, OHIO, ASSIGNOR TO WESTINGHOUSE ELECTRIC
& MANUFACTURING COMPANY, A CORPORATION OF PENNSYLVANIA.

INCLOSED SWITCH.

Application filed June 25, 1927. Serial No. 201,322.

My invention relates to inclosed switches and particularly to switches for controlling small motor and lighting circuits.

An object of my invention is to provide an inclosed switch of simple construction wherein the housing is protected from the arc incident to the separation of the switch contacts, and wherein the arc is prevented from grounding through the switch housing.

Another object of my invention is to provide an inclosed switch having the above noted characteristics, wherein a pressed metal barrier is mounted upon an insulating operating arm of the switch, and wherein the barrier may be mounted upon a switch of standard construction without necessitating material changes in the switch design.

These and other objects that will be made apparent throughout the further description are obtained by means of a switch apparatus hereinafter described and illustrated in the accompanying drawings, wherein:

Figure 1 is a plan view of the switch apparatus with a portion of the cover cut away.

Fig. 2 is a longitudinal section through the switch housing taken on the line II-II of Figure 1, and showing the switch apparatus embodying my invention in side elevation.

Referring to the drawings, the inclosed switch comprises a metal housing 3 having side walls 4 and 5 and end walls 6 and 7. The housing is provided with a cover 8 that is hinged to the housing by means of hinge rivets 9.

An insulating switch block 11 is secured to the bottom wall 12 of the housing and is provided with a fuse receptacle 13 for receiving a standard screw plug fuse, (not shown). A knife switch 14 is also mounted upon the insulating base and comprises a hinge jaw 15 in which a knife switch blade 16 is pivoted, and which engages a contact jaw 17. The fuse receptacle 13 is provided with a terminal 18, and a terminal 19 is connected to the contact jaw 17, the feed conductors being connected to the terminals in such manner that current passes through the fuse receptacle, fuse plug and the switch blade.

The switch blade 16 is provided with an insulating operating arm 21 that is riveted thereto and is provided with a notch 22 for receiving an operating bail 23 that is jour-

nalled in the side walls 4 and 5 of the housing, and which is provided with an integral operating handle 24 which extends exteriorly of the housing. The switch is moved to the open position A, indicated in dotted lines, by means of the operating handle, and as shown in Figs. 1 and 2 the switch is in the closed position.

In order to reduce the over-all dimensions of switches of this character, the side walls of the housing are, of necessity, disposed relatively close to the contact jaw of the switch and it has been found that under certain abnormal current conditions, the arc drawn between the switch jaw 17 and the switch blade 16 jumps across the space between the switch jaw and the side wall 4 of the housing and causes the arc to be grounded through the switch housing which is usually grounded. When the arc grounds through the switch housing, it endures until the circuit is interrupted by the fuse, with the result that the contact jaw is destroyed by the excessive heat of the arc.

In order to obviate this condition, I provide a stamped metal barrier 25 having an extension 26 which constitutes a bracket which is securely riveted to the insulating operating arm 21 by means of rivets 27. The free end of the barrier is offset and spaced from the switch jaw 17 and when the switch is in the closed position, occupies a position between the contact jaw 17 and the side wall 14 of the housing. In the event that an arc is drawn when the switch is being opened, the barrier prevents the arc extending to the side wall of the housing and has a cooling influence thereon. It has been found that the barrier prevents grounding of the arc under all operating conditions to which the switch is normally subjected.

As shown, the insulating base, is not directly attached to the bottom wall of the housing but is mounted upon a metal plate 27 of U-shape and having side wings 28 and 29, the plate 27 being detachably secured to the bottom wall 12 by means of screws 31. It will be understood that the wings 28 and 29 are considered as a part of the side wall 105 of the housing, the wings being in conductive engagement therewith and consequently grounded through the side wall.

It is apparent from the foregoing that the barrier may be attached to an inclosed

switch of standard construction with very small additional cost.

While I have illustrated but one embodiment of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. Switch mechanism comprising a housing, an insulating base therein, a contact member mounted on the base, a movable switch member for engaging the contact member, and a barrier carried by the switch member and disposed between the contact member and a wall of the housing, the said barrier being insulated from the said switch member.

2. Switch mechanism comprising a hous-

ing, an insulating base therein, a contact member mounted on the base, a movable switch member for engaging the contact member, an insulating operating member for the switch member and a barrier secured to the said operating member and disposed between the said contact member and a wall of the said housing.

3. Switch mechanism comprising a housing, an insulating base therein, a contact jaw mounted on the base, a movable switch blade for engaging the contact member, an insulating operating member secured to the switch blade and a metal barrier secured to the said operating member and disposed between the said contact member and a wall of the said housing.

In testimony whereof, I have hereunto subscribed my name this 25th day of May, 1927.

HALDIMAND W. NEAL.
